UNITED STATES PATENT OFFICE

WILBUR A. FISHER, OF TEMPLE, TEXAS

DESIGN FOR A CONDIMENTS HOLDER

Application filed July 22, 1930. Serial No. 36,441. Term of patent 14 years.

To all whom it may concern:

Be it known that I, WILBUR A. FISHER, a citizen of the United States, residing at Temple, in the county of Bell and State of Texas, have invented a new, original, and ornamental Design for a Condiment Holder, of which the following is a specification, reference being had to the accompanying drawing, forming part thereof.

I claim:

The ornamental design for a condiment holder, as shown.

WILBUR A. FISHER.
